UNITED STATES PATENT OFFICE

154,346

DESIGN FOR AN ENEMA TRAY

Virginia Campbell Thompson, Arlington
County, Va.

Application August 27, 1947, Serial No. 141,085

Term of patent 7 years

(Cl. D83—1)

To all whom it may concern:

Be it known that I, Virginia Campbell Thompson, a citizen of the United States, residing at 202 North Oakland Street, in the county of Arlington and State of Virginia, and whose post office address is 202 North Oakland St., Arlington, Virginia, have invented a new, original, and ornamental Design for Enema Trays, of which the following is a specification, reference being had to the accompanying drawing, forming part thereof.

Fig. 1 is a perspective view of an enema tray, showing my new design;

Fig. 2 is an end elevation thereof taken from the left of Figure 1.

I claim:

The ornamental design for an enema tray, as shown.

VIRGINIA CAMPBELL THOMPSON.
